US00D975376S

(12) **United States Design Patent** (10) **Patent No.:** **US D975,376 S**
(45) **Date of Patent:** **** Jan. 10, 2023**

(54) **APPARATUS FOR PET HAIR REMOVAL**

(71) Applicant: **Towerstar Pets, LLC**, Malvern, PA (US)

(72) Inventors: **Fernando Becattini, Jr.**, Malvern, PA (US); **Jacquelyn N. Becattini**, Malvern, PA (US); **Fernando Becattini, Sr.**, Devon, PA (US); **Steve A. Copeland**, Barrie (CA); **Nicholas Teixeira**, Angus (CA)

(73) Assignee: **TOWERSTAR PETS, LLC**, Malvern, PA (US)

(**) Term: **15 Years**

(21) Appl. No.: **29/842,145**

(22) Filed: **Jun. 10, 2022**

(51) **LOC (14) Cl.** **30-99**

(52) **U.S. Cl.**

USPC **D30/159**; D30/158

(58) **Field of Classification Search**

USPC D30/158, 159, 199, 162, 106; 119/625, 119/633, 600, 617, 628, 632, 631, 613, 119/618, 619, 620, 611; 132/126, 142, 132/143, 155; 30/114, 130, 301, 305, 30/315, 316, 299, 303, 306, 169, 322, 31, 30/30, 279.2, 280, 287, 294, 199, 30/329-344, 346.56, 346.61, 355, 357, 30/172; D7/672-676, 687, 686, 634, 619, D7/688, 653; 425/298; 426/503; D4/136, 127, 124-126, 116-118, 199, D4/194, 137; D32/42, 25, 41, 48, 40, 35, D32/46; D23/261; 2/160; 172/379, 380; D6/415, 410, 411; 294/1.3, 1.5, 55, 99.1, 294/49, 7, 9, 99.2, 118, 119, 19.2, 52; 209/418; D24/211, 147; D21/532, 398; D19/36; 34/381, 103, 104, 107; D11/104, 86; 56/400.01, 400.1, 400.17,

(57) **CLAIM**

The ornamental design for an apparatus for pet hair removal, as shown and described.

DESCRIPTION

FIG. 1 is a front, top, left side isometric perspective view of an apparatus for pet hair removal in accordance with our design;

FIG. 2 is a front, top, right side isometric perspective thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines illustrate portions of the apparatus for pet hair removal which form no part of the claimed design.

1 Claim, 6 Drawing Sheets
